US0D1070595S

(12) **United States Design Patent** (10) Patent No.: **US D1,070,595 S**
Okamura (45) Date of Patent: ** Apr. 15, 2025

(54) **PACKAGING CONTAINER**

- (71) Applicant: **TENGA Co., Ltd.**, Tokyo (JP)
(72) Inventor: **Keisuke Okamura**, Tokyo (JP)
(73) Assignee: **TENGA CO., LTD.**, Tokyo (JP)
(**) Term: **15 Years**
(21) Appl. No.: **35/518,668**
(22) Filed: **Sep. 14, 2023**

(80) **Hague Agreement Data**

- Int. Filing Date: **Sep. 14, 2023**
Int. Reg. No.: **DM/232054**
Int. Reg. Date: **Sep. 14, 2023**
Int. Reg. Pub. Date: **Oct. 13, 2023**

(30) **Foreign Application Priority Data**

- Apr. 6, 2023 (JP) 2023-007152
